CHECK VALVE

Morris Katcher, New York, N. Y.

Application November 10, 1943, Serial No. 509,645

1 Claim. (Cl. 251—144)

1

This invention relates to a check valve, especially one which is suitable for use in a fuel pump for internal combustion engines. In pumps of this type, it has been a practice to use valves which can be pushed in with a forced fit into the passages of the pump. The principal part of valves of this type is made of a sheet metal stamping of a rather complicated form. The assembling of the parts of the valve also offers difficulties. Valves of this type can be seen at 47 and 49 in Fig. 1 of Patent No. 2,036,452. It is an object of the present invention to construct a valve in which the two principal parts are formed from simple sheet metal stampings, namely, a trough-shaped ring and a cage which can be given a forced fit in the ring. The outside surface of the ring is substantially cylindrical, so that it can be readily given a forced fit in the circular passages of a fuel pump.

Other objects and advantages will become apparent upon further study of the description and drawing, in which:

Fig. 1 is a substantially median vertical section through a fuel pump showing two of my valves set therein;

Fig. 2 is a plan view of the inlet side of the valve with a portion broken away to show the side of the plate beneath;

Fig. 3 is a section taken along the line 3—3 of Fig. 2;

Fig. 4 is a plan view of the outlet side of the valve, and

Fig. 5 is a section taken similarly to Fig. 3 of a modified form of the valve.

Near the end of inlet nipple 6 of the fuel pump is set one of my valves, valve 7, with a forced fit therein, the ring 8 of the valve being pushed against shoulder 9. Inlet nipple 6 leads to a chamber 10 in which is mounted diaphragm 11. Outlet nipple 12 leads the fuel from chamber 10. Outlet nipple 12 is set another of my valves, valve 13, which has a mounting similar to that of valve 7. Valve 7 permits the fuel to enter chamber 10 but not to pass out to the left therefrom. Valve 13 permits the fuel to leave chamber 10 and to enter nipple 12 but not to return. Diaphragm 11 is held between washers 14 which are attached to the upper end of rod 15. The lower end of rod 15 has a slot 16 in which one end of crank 17 plays. Crank 17 is fixed at its other end to rock shaft 18, said shaft being rocked by mechanism not shown but which is well known to the art wherein fuel pumps are used. The reciprocation of crank 17 causes rod 15 to flex up and down effecting the intake

of fuel through valve 7 and its discharge through valve 13.

Valve 7 consists of a ring or crown 8 of relatively heavy gauge metal. Ring 8 is substantially trough-shaped in cross section. A retainer cage 19 of relatively lighter gauge metal has a cylindrical upper portion 20 which is given a forced fit with the inside of the outer rim 21 of ring 8, Fig. 3. The inside surface of rim 21 is substantially cylindrical. Arms 26 extend upward from a substantially flat base 22 to join the latter with the cylindrical upper portion 20. A spring 23 is set upon base 22 and at its upper end presses or seats a polygonal plate 25 against the bottom edge of inner rim 24 of ring 8. Parts 8, 19 and 25 are readily stamped from sheet metal and easily assembled with spring 23. In its broader sense base 22 is merely a transversely extending portion of cage 19 not necessarily flat or imperforate.

In Fig. 5 is shown a valve of modified construction. It comprises a relatively heavy gauge ring 31 of sheet metal of trough-shaped cross section, the trough being of V-form, the outer rim 21 of which instead of having a cylindrical inner surface as with ring 8 of Fig. 3, has a substantially truncated conical one. Cage 28 has a flat base 29 as before, with arms 30 extending upward therefrom. The inner rim 32 of ring 31 has its outer surface also of substantially truncated conical form but with a flatter conical angle. Upper portion 33 of cage 28 before it was forced into ring 31 was inscribable in a cylinder as shown for the upper cylindrical portion 20 of Fig. 3. As cage 28 is forced into ring 31, the top of portion 33 first strikes the upper part of the outer surface of inner rim 32 and then is spread outward to engage the inner surface of outer rim 21. Spring 23 and plate 25 are similar in construction and function to those shown in Figs. 3 and 4.

In operation, liquid entering the valve passes inward through rings 8 or 31 and pushes down plate 25 away from the ring against the pressure of spring 23. Once this is done the liquid passes by the edge of plate 25 and through the spaces between the arms of cages 19 or 28. When fluid enters the valve in the reverse direction, plate 25 is pushed against ring 8 in the valve of Fig. 3 and against ring 31 in the valve of Fig. 5, in both cases blocking the flow of fluid through the valve.

I claim:

A check valve comprising a ring, trough-shaped in cross section, said trough being substantially V-shaped providing an inner and an outer rim

extending axially of said ring, a cage having a substantially transversely extending base and a portion extending generally axially from the base to the ring, said rims extending with their free edges toward the base, the inside surface of the outer rim being in the form of a truncated cone with its largest diameter away from the free edge of said latter rim, the outside surface of the inner rim also being in the form of a truncated cone but at a greater inclination with the axis of the ring than said inside surface, said cage portion extending into the ring with a tight fit with the entire inside surface of the outer rim of the ring, a transversely extending member movable within the cage to seat against the free edge of the inner rim of the ring, and a spring between the member and said base, normally holding the member in seated position against said inner rim.
